UNITED STATES PATENT OFFICE.

SAMUEL H. ROBESON, OF HENDERSON, TENNESSEE.

VEHICLE-AXLE.

No. 797,322.

Specification of Letters Patent.

Patented Aug. 15, 1905.

Application filed August 30, 1904. Renewed May 31, 1905. Serial No. 263,158.

To all whom it may concern:

Be it known that I, SAMUEL H. ROBESON, a citizen of the United States, residing at Henderson, in the county of Chester and State of Tennessee, have invented certain new and useful Improvements in Vehicle-Axles, of which the following is a specification.

This invention relates to axles designed chiefly for coöperation with vehicle-wheels, the purpose being to provide novel means for taking up wear between the spindle and hub and yet admit of tightening the axle-nut by means of a wrench or spanner in the accustomed manner, cone-bearings being provided for the wheel and dust-excluding means employed to prevent grinding of the bearings.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a longitudinal section of a hub, axle-skein, and adjunctive parts, showing the axle-arm or spindle in full embodying the invention. Fig. 2 is a detail perspective view of the axle-arm and coöperating parts separated and arranged in a group.

Corresponding and like parts are indicated by the same reference characters in both views of the drawings.

The axle is indicated at 1, and its arm or spindle at 2. An enlargement 3 is formed with the axle at a point between it and the spindle 2 and is threaded, as shown at 4, and provided with a cone, as shown at 5. The outer end of the axle-arm or spindle is reduced and threaded, as indicated at 6, and is adapted to receive the axle-nut 7, a series of washers 8, and a jam-nut 9, said parts 8 and 9 constituting, in effect, sections of the spindle or axle-arm to admit of its lengthening or shortening to effect proper spacing of the cones 5 and 10, the latter being at the inner end of the axle-nut 7. The washers 8 are of different thicknesses to provide for proper spacing of the cones 5 and 10 to adapt them to the distances apart of the flaring recesses 11 and 12 at opposite ends of the axle-box 13 or hub, as the case may be. A sleeve 14 is provided for the enlargement 3 and is internally threaded

to match the screw-threads 4 of said enlargement, upon which it is adjustable, to admit of a snug joint being maintained between the hub and axle, so as to exclude dust and foreign matter from the inner cone-bearing. The sleeve 14 is secured in the adjusted position by any suitable means, and, as shown, a set-screw 15 is provided and threaded into an opening formed in a side of the sleeve, the inner end of said set-screw being adapted to bind upon the threads 4.

The axle-box 13 or eye of the hub is enlarged at opposite ends, as shown at 11 and 12, to receive the cone-bearings 5 and 10, the intermediate portion being spaced from the axle-arm or spindle. The axle-nut 7 is provided at its inner end with the cone 10 and intermediate of its ends with an outer flange 16, which is channeled upon its inner face to receive a washer 17. The axle-nut is adapted to screw upon the threaded extension 6 of the axle-arm and is limited in its inner movement by coming in contact with the jam-nut or section 9. This occurs when the cones 5 and 10 are spaced apart a distance corresponding approximately to the distance between the recesses 11 and 12, the adjustment being such as to prevent binding of the bearings and yet admit of the wheel turning freely without any lost motion or play. The adjustment is determined by test, and should the wheel have too much play upon the spindle after the axle-nut has been screwed home it is necessary to either substitute a thinner washer for one of the parts or sections or to remove a washer. On the other hand, should the bearings bind either before or after the axle-nut is screwed home it is necessary either to add a washer 8 or to replace one of said washers by a thicker section. This interchange of washers or sections results practically in lengthening or shortening the axle-arm or spindle, as will be readily comprehended.

In the preferable construction the cone 5 is an integral part of the axle and spindle. A washer 18 corresponding to the washer 17 is inserted in an enlargement at one end of the sleeve 14 adjacent to the hub, so as to insure the formation of a tight joint, which is essential for the exclusion of dust from the bearings.

Having thus described the invention, what is claimed as new is—

In combination, an axle provided with a spindle having a threaded extension at its outer end and an integral enlargement at a

point between the spindle and axle, said enlargement having a portion threaded and its outer end tapered to form a cone, a sleeve mounted upon the threaded portion of said enlargement, means for securing said sleeve in an adjusted position, a series of washers varying in thickness slipped upon said threaded extension, a jam-nut for confining said washers, said jam-nut and washers forming an adjustable extension of the axle-arm to admit of its lengthening or shortening, a hub slipped upon the axle-arm and having its opening outwardly flared at opposite ends, the inner end of the hub being received by the

sleeve above mentioned, an axle-nut mounted upon said threaded extension and having an integral cone at its inner end and limited in its inward movement by the aforementioned jam-nut, and washers applied to said sleeve and axle-nut to insure the formation of a tight joint between the hub and axle-arm, substantially as specified.

In testimony whereof I affix my signature in presence of two witnesses.

SAMUEL H. ROBESON. [L. S.]
